UNITED STATES PATENT OFFICE.

ESTÉBAN GORRITI AIZCORVE, OF CAIBARIEN, CUBA.

APPARATUS FOR THE MANUFACTURE OF SUGAR.

1,358,132.

Specification of Letters Patent.

Patented Nov. 9, 1920.

Application filed January 5, 1918. Serial No. 210,565.

To all whom it may concern:

Be it known that I, ESTÉBAN GORRITI AIZCORVE, a subject of the King of Spain, residing at Caibarien, Cuba, have invented new and useful Improvements in Apparatus for the Manufacture of Sugar, of which the following is a specification.

My invention relates, in general, to the industry of the manufacture of sugar from sugar cane, and makes reference more particularly to that class of apparatus employed in said industry in order to clarify the juices of the sugar cane, separating from the same the impurities which it contains in suspension; and the prime object of the invention is to provide an apparatus to accomplish said clarification, of a simple construction, which can be easily and economically installed, handled with very little effort and efficient in operation.

It is known that the clarification of the saccharine juice is effected by heating the juice after neutralizing its acidity, in suitable apparatus. In these apparatus, called purifiers, the solid and lighter substances contained in suspension in the juices, rise to the top, heaping up on the liquid surface by the elevation of the temperature, and the heavier materials are precipitated to the bottom, leaving an intermediate zone of juice relatively clear and free from impurities. In order to carry out this depuration or clarification it has been necessary to install a considerable number of purifiers requiring the consumption of a considerable amount of steam and resulting in a costly operation and waste of time. Moreover, if it be taken into consideration that when the separation of the solid particles is accomplished by heat it is necessary to allow the liquid to stand for a considerable length of time in order to permit the precipitation of the remaining particles and the consequent separation of the same.

As will be understood by the brief explanation just made regarding the manner actually employed of clarifying the saccharine juices, this operation is costly and dilatory, and the juice obtained is not free of impurities; and to overcome this difficulty I have designed the present invention, which essentially consists in a modification of the apparatus usually employed for evaporating the water contained in the juice, so that the clarification of same and the evaporation of

said water is performed at one and the same time in the above mentioned apparatus, in a manner substantially uninterrupted or continuously, eliminating completely the use of the purifiers and the inconveniences resulting therefrom.

The invention is described in relation to the figures of the accompanying drawings, in which—

Figure 1 is a perspective view of a vacuum evaporating apparatus, modified according to my invention; Fig. 2 is an upper plan view of the same; Fig. 3 shows a side elevation of the body of a single effect apparatus in which my invention is applied; Fig. 4 represents a perspective view of an apparatus for operating the clarification and the evaporation simultaneously without the use of vacuum; and Fig. 5 shows a top plan view partially broken, of the apparatus illustrated in Fig. 4.

In all the figures the identical parts are indicated by the same characters of reference.

Substantially my invention is designed to separate into two parts the evaporating apparatus employed until now, which comprises a lower chamber for heating the liquid and a superior or upper chamber wherein the vacuum is applied, uniting them both chambers by means of a closed channel, as will be seen in the following description.

The numeral 1, shows the heating chamber of the juice, which is to be purified. This chamber is constructed similarly to the body or lower chamber of any evaporator in use, and therefore it may be provided with a double bottom, or serpentine or tubes coils or worm or any other suitable means for circulating the steam and heating the liquid in the chamber.

At the top of said chamber is bolted the channel or closed conduit 2, preferably constructed in a rectangular section, extending from one side of the chamber 1. Said channel, which is connected at one end with the said chamber 1, is provided at the other end with a rectangular body 3, projecting upward to which is joined the body 4, which constitutes the vacuum chamber of the evaporating apparatus. The bottom 5 of the channel or conduit 2 is inclined and extends downwardly from the chamber 1 and adjacent to the lower end of the bottom of the channel or conduit 2 a valve 6 is pro-

vided to permit the juice that is to be clarified to flow into the channel until the chamber 1 is filled and the channel 2 up to a certain height, for instance, a little above the 5 middle of the height of the channel, the valve being then closed so that an air space is left between the surface of the liquid and the top of the channel 2.

When the steam is applied to the heating 10 chamber 1, the temperature of the liquid in the chamber and in the channel 2, rises, and a circulation or current is established, flowing from the heating focus in the chamber, toward the other end of the channel, and 15 this current drives back against the vertical wall 7, which is the limit of the channel 2 all the solid particles and foreign matter contained in suspension in the cold juice coming through the valve 6, reuniting at 20 this point not only the heavier substances but the lighter ones, and from thence they are removed by any convenient means (not shown) through the opening 8 provided in the vertical wall 7. The opening 8 is controlled by a door 8^a, as shown in Fig. 3.

It is evident that in the heater chamber 1, a pure and clear juice is found, free from all impurities because those contained in the cold liquid entering through the valve 6, are held back before arriving at the chamber by the flow of liquid resulting from the higher temperature of the liquid in the chamber 1 than in the channel 2, as explained already. The heating of the liquid in the chamber 1 30 results in a boiling or agitation of the liquid and a flow of the same from the heating chamber, the lighter particles being carried along the closed conduit toward the outer end thereof by the foam on the surface of 35 the liquid, while the heavier particles are carried downwardly and outwardly along the inclined bottom which facilitates the movement of the heavier particles away from the heating chamber and which tends 40 to prevent them from entering the said heating chamber. This liquid now clarified and free from a great deal of water, is carried through the valve 9, pipe 10, and valve 11, from the chamber 1 to another similar evaporating apparatus, in which it is again submitted to the same operations, losing much 45 more water and becoming clearer and purer and from there is carried to the third evaporator by valve 13, pipe 14 and valve 15.

By the foregoing description as well as by the examination of Figs. 1, 2 and 3, will be seen that the description has been made as if the invention had been applied to an evaporating apparatus of triple effect 55 wherein is employed the vacuum in order to facilitate the evaporation of the water and the concentration of the saccharine elements, but it is evident that the modification described may be also employed in a simple effect or in a multiple effect, as de-

sired, using for it, respectively, a simple or several modified apparatus, conveniently arranged.

In like manner my invention may be adapted to operate without the use of the 70 vacuum, and in this form of the invention shown in the Figs. 4 and 5, an adequate modification is illustrated.

This modification consists in the suppression of the rectangular body 3 that projects over the end of the channel 2, and in its place a raised body 16 is provided, and therein an opening 17 is made, so as to allow the escape into the atmosphere of the vapors and gases produced by the raising of the 80 temperature of the liquid.

The manner of operating this apparatus is similar to that already described in relation with vacuum evaporators.

A single apparatus comprising this modification may be also employed, or a plurality arranged in a convenient manner, in order that the liquid may pass through.

Heat may be applied directly to the heating chamber, or the chamber may be provided with a double bottom, or serpentine or coils or worm or any other device suitable for circulating steam and heating the liquid.

It is obvious that minor changes may be 95 made in the form and construction of this invention without departing from the material principles thereof. It is not therefore desired to confine the invention to the exact form herein shown and described, but to 100 include all such as properly come within the scope of the appended claims.

Having thus described the invention, what is claimed as new, is:

1. In apparatus for clarifying the juices 105 of sugar comprising a closed conduit, a heating chamber located beneath and connected with one end of the conduit, a vacuum chamber arranged at the other end of the said conduit at the upper portion thereof, 110 said conduit being provided at such end with a discharge opening, an outlet pipe connected to the heating chamber, and an inlet pipe connected to the conduit adjacent the said discharge opening.

2. An apparatus for clarifying and evaporating saccharine juices comprising a closed conduit, a heating chamber located below and connected with one end of the conduit, said conduit being provided at its 115 other end with a discharge opening, a closure for said opening, an outlet pipe connected with the said heating chamber, and an inlet pipe connected to the said conduit at the end remote from the heating chamber.

3. An apparatus for clarifying the juices of sugar comprising a heating tank, a horizontally disposed channel connected to the top of said tank at one end thereof and having a discharge opening at the end remote 120

from said tank, the bottom wall of said channel being inclined upwardly toward the tank, an outlet pipe communicating with said tank at a point below said channel, and an inlet pipe communicating with said channel at the end remote from and above said tank for admitting cool juice to said channel.

4. An apparatus for clarifying and evaporating saccharine juices, comprising a heating chamber, a closed channel connected to the upper portion of the heating chamber, said channel having its bottom inclined downwardly away from said chamber, and means for admitting juices at the low end of said channel.

5. An apparatus for clarifying and evaporating saccharine juices, comprising a heating chamber, an unobstructed channel connected to the upper portion of the heating chamber, said channel having its bottom in-

clined downwardly away from said chamber, and means for admitting juices at the low end of said channel.

6. An apparatus for clarifying and evaporating saccharine juices comprising a closed conduit having an inclined bottom, a heating chamber located beneath and connected with the conduit at the upper end of the bottom and provided with an outlet, said conduit being provided at the end remote from the heating chamber with a discharge opening, and means also located at such end of the conduit for introducing liquid into the same.

In testimony whereof I have signed my name to this specification in the presence of two subscribing witnesses.
